UNITED STATES PATENT OFFICE.

HENRY A. SEYMOUR AND WILLFORD H. NETTLETON, OF BRISTOL, CONN.

IMPROVED RIVETING-HAMMER.

Specification forming part of Letters Patent No. 102,871, dated May 10, 1870.

To all whom it may concern:

Be it known that we, HENRY A. SEYMOUR and WILLFORD H. NETTLETON of Bristol, in the county of Hartford and State of Connecticut, have invented a new and useful Improvement in Riveting-Hammers, of which the following is a specification.

Our invention is designed to be used for riveting lock-work for clocks; and it consists in the employment of a presser-spring arranged in combination with a riveting-punch or hammer, and projecting below the end of the same, as hereinafter described.

In the accompanying drawings, Figure 1 is a front elevation of our invention, and Fig. 2 a side elevation of the same.

A designates an ordinary pair of spring-gripping-jaws, which, by any proper mechanism, can be made to grip the wire a, which is to be riveted into the shaft b.

B designates a heading-punch, the face of which may be either plain, concave, or countersunk, as desired. The punch B is secured in a proper head or hammer, C, which may be arranged to swing on pivots or slide in ways, so that it can be made to descend with sufficient force to head the wire a.

c designates a presser-spring, which is secured firmly to the hammer C and moves with it. The spring c is slotted at d to admit the

end of the punch B, the lower part of the spring being in advance of the face of the punch.

The operation is as follows: The wire a is gripped and held in the jaws A, with its end projecting from the same a little more than the diameter of the shaft b. The shaft is placed with the hole, which has been previously drilled to receive the wire a, immediately over the end of the same, when the hammer is made to descend. The spring c, being in advance of the punch B, strikes the shaft b, and presses it down upon the wire until it rests upon the jaws A, when the spring depresses or yields and allows the punch to advance through the slot d, and head the wire in the usual manner. Without the employment of the spring c it is necessary to drive the shaft b onto the wire a with a hand-hammer or otherwise previous to the fall of the punch B.

We claim as our invention—

The combination of the jaws A, presser-spring c, heading-punch B, and hammer C, all constructed and operating together substantially as described.

HENRY A. SEYMOUR.

WILLFORD H. NETTLETON.
